(57) **CLAIM**

The ornamental design of a filter housing header, as shown and described.

DESCRIPTION

FIG. 1 is an isometric view of a filter housing incorporating our new design;

FIG. 2 is a front elevation view thereof;

FIG. 3 is a left side elevation view thereof, the right side elevation view being a mirror image;

FIG. 4 is a rear elevation view thereof;

FIG. 5 is a top plan view thereof; and,

FIG. 6 is a bottom plan view thereof.

The broken line showing is for illustrative purposes only and forms no part of the claimed design.
